UNITED STATES PATENT OFFICE.

LOUIS HENRY SCHÄFER, OF NEW ORLEANS, LOUISIANA.

AUTOMATIC MAIL BOX.

Application filed December 17, 1926. Serial No. 155,479.

The invention relates to a mail box, and more especially to the class of mail chutes designed for incoming and outgoing mail matter.

5 The primary object of the invention is the provision of a device of this character, wherein incoming mail can be delivered with dispatch and the outgoing mail automatically discharged, thereby saving time on the 10 part of the mail carrier, both in the collection and delivery of mail matter to a house or other edifice, the device being of novel form to have the same readily accessible both to the occupants of the house or edifice 15 and to the mail carrier.

Another object of the invention is the provision of a device of this character, wherein mail can be conveniently and easily delivered by a carrier to the interior of the 20 house or edifice and the outgoing mail automatically discharged for its collection by such carrier, thus eliminating double duty on the part of said carrier.

A further object of the invention is the 25 provision of a device of this character, wherein the same is water-tight, wind-tight, ornamental, indestructible, automatic, absolutely safe and will assure the reception and delivery of mail, both incoming and outgoing mail matter, with dispatch, thereby 30 relieving the mail carrier from excessive or double duty in the reception and delivery of mail matter.

A still further object of the invention is 35 the provision of a device of this character, which is extremely simple in construction, thoroughly reliable and efficient in its purpose, strong, durable, neat and attractive in appearance, and inexpensive to manufacture 40 and install.

With these and other objects in view, the invention consists in the features of construction, combination and arrangement of parts, as will be hereinafter more fully described, illustrated in the accompanying drawing, and pointed out in the claims hereunto appended.

In the accompanying drawing:—

Figure 1 is a fragmentary elevation, showing fragmentarily the outer wall of a building, with the mail box constructed in accordance with the invention installed.

Figure 2 is an enlarged sectional elevation taken on the line 2—2 of Figure 1 looking 55 in the direction of the arrow.

Figure 3 is a fragmentary detailed sectional view taken approximately on the line 3—3 of Figure 2 looking in the direction of the arrow.

Similar reference characters indicate corresponding parts throughout the several views in the drawing.

Referring to the drawing in detail A designates generally a portion of the outer wall of a building or other edifice, which 60 may be of any conventional form and B the inner wall, which is spaced from said outer wall as usual and also may be of any well known construction. Formed in the outer and inner walls A and B are suitable 65 openings to accommodate the mail box or device constituting the present invention, which will be hereinafter more fully described.

The mail box or device comprises an outer 70 plate, in the form of an escutcheon plate 5 having a marginal flange 6 constituting a frame adapted to be set in the opening in the outer wall A, to completely occupy such opening which is correspondingly shaped to 75 the frame 6. This frame 6 is made fast in the opening in any suitable manner. Formed in the plate 5 transversely thereof are superposed elongated upper and lower slots 7 and 8, respectively. Leading through the 80 inner wall to the upper slot 7 is an outwardly inclined mail delivery chute 9, which can be of any approved type, so that mail matter delivered or deposited in the said chute from within the building or edifice 85 will be caused to gravitate to the slot 7 in the plate 5 and discharge outwardly therefrom without the building or edifice.

Leading from the lower slot 8 inclined inwardly and extending through the inner 90 wall B is a lower chute 10 so that mail matter introduced through the lower slot 8 in the plate 5 will pass through the chute 10 downwardly and be discharged within the building or edifice. About the inner or open 95 ends of these chutes 9 and 10 and suitably secured to the inner wall B are slotted face plates 11, these being in the form of escutcheon plates.

Normally closing the slots 7 and 8 are the 100 upper and lower doors or louvers 12 and 13, respectively, the upper door or louver being formed at opposite ends with cam wings 14 in which are engaged pintles or pivots 15, these also being engaged in brackets 16 110

formed on the plate 5 and in this manner the said upper door 12 is eccentrically mounted so that the same will gravitate to closed position for normally closing the slot 7. This door 12 has on its outer face suitable indicia 16 indicative of outgoing mail. The cam ears 14 at their upper portions are extended beyond the door 12 to constitute stops 18 to abut the inner face of the plate 5 so as to limit the closing movement of said door 12 as will be clearly apparent in Figure 2 of the drawing.

Formed on the lower door 13 at opposite ends thereof are weight ribs 19, and passed through suitable ears 19' between these, above the top edge of the door is a pivot 20 which is also passed through brackets 21 extending inwardly from the plate 6 and in this manner the said door 13 is eccentrically pivoted for swinging movement to open inwardly of the chute 10 and to gravitate to normally closed position for closing the slot 8 in said plate 5. The ribs 19 are extended to provide tripping arms 22 arranged in the path of the cams 14, so that on the opening of the door 13 the arms 22 will act upon the cams 14 to cause the door 12 to automatically open and thereby discharge outgoing mail from the chute 9, when incoming mail is deposited through the slot 8 on opening the door 12 into the chute 10 for the delivery of such incoming mail to the interior of the building or edifice.

It will be apparent that to permit the discharge of outgoing mail from the chute 9 the lower door 13 can be pushed inwardly, causing the upper door 12 to automatically swing outwardly for the discharge of mail matter from said chute 9 and the incoming mail can be conveniently deposited through the lower slot 8 into the chute 10 to be delivered within the building or edifice.

Surrounding the pivot 20 hanging the lower door is a coiled tension spring 23 which has one end playing against the door 13 and its other end against the plate, so that in this manner the said door is retained positively closed or in other words is held under tension as will be clearly obvious.

From the foregoing it is thought that the construction and manner of operation of the device will be clearly understood and therefore a more extended explanation has been omitted.

55 What is claimed is:—

1. The combination with a pair of reversely disposed chutes adapted to be confined within a wall of a building and opening within and without the same, of a slotted plate adapted to be mounted on the outer face of the wall of said building and having a pair of slots communicating with said chutes, superposed, oppositely movable doors swingingly supported upon said plate and normally closing the slots therein, and

means on said doors to coact with each other to effect the swinging outwardly of one door on the inward manual swinging of the other door, the said means on one door being free of connection with the said means on the other door. 70

2. The combination with a pair of reversely disposed chutes adapted to be confined within a wall of a building and opening within and without the same, of a slotted plate mounted on the outer face of the wall of said building and having a slot communicating with each of said chutes, doors swingingly supported upon said plate and normally closing the slots therein, said doors so arranged in superposed relation and oppositely movable with respect to each other, means on said doors to coact with each other to effect the swinging outwardly of one door on the inward manual swinging of the other door, said means on one door being free of connection with the means on the other door, and means eccentrically supporting said doors to effect the gravitation thereof to closing position. 90

3. The combination with a pair of reversely disposed chutes adapted to be confined within a wall of a building and opening within and without the same, of a slotted plate mounted on the outer face of the wall of said building and having superposed slots communicating with said chutes, superposed, oppositely movable doors swingingly supported upon said plate and normally closing the slots therein, means on said doors to coact with each other to effect the swinging outwardly of one door on the inward manual swinging of the other door, the said means on one of said doors being free of connection with the said means on the other of said doors, means eccentrically supporting said doors to effect the gravitation thereof to closing position, and weight means on the inwardly swinging door. 100

4. The combination with a pair of oppositely extending chutes adapted to be confined in a support and opening within and without the latter, of a slotted plate mounted against the outer face of said support and having a pair of superposed slots communicating with said chutes, superposed, oppositely movable doors supported from said plate, one of said doors normally arranged within one of said slots to close the same and the other of said doors normally arranged against the inner face of said plate for closing the other of said slots, said doors having inwardly extending means free of connection with and co-acting with each other to effect the swinging outwardly of one door on the inward manual swinging of the other door, and means to provide for the gravitation of the doors to closing position. 115

5. The combination with a pair of oppositely extending chutes adapted to be mount- 120

ed within a support therefor and opening within and without the support, of a plate secured to the outer face of the support and provided with a pair of superposed slots 5 communicating with said chutes, superposed, oppositely movable doors swingingly supported from said plate, one of said doors normally arranged in one of said slots for closing it and the other of said doors normally arranged against the inner face of 10 said plate for closing the other of said slots,

cam members extending inwardly from one of said doors, and weight means arranged on the inner face of the other of said doors and provided with tripping arms, said cam members and tripping arms coacting to effect the swinging outwardly of one door on the inward manual swinging of the other door. 15

In testimony whereof, I affix my signature hereto.

LOUIS HENRY SCHÄFER.
